United States Patent

Des. 239,349

Patented Mar. 30, 1976

239,349

SHOWCASE

Phillip Small, 5000 Oak, Apt. 1015,
Kansas City, Mo. 64112

Filed Apr. 14, 1975, Ser. No. 567,742

Term of patent 14 years

Int. Cl. D6—04; D20—02
U.S. Cl. D6—152

Fig.1.

Fig.2.

Fig.3.

Fig.4.

FIG. 1 is a side elevational view of a showcase embodying my new design, the side opposite being a mirror image thereof;

FIG. 2 is a front elevational view thereof;

FIG. 3 is a rear elevational view thereof; and

FIG. 4 is a top plan view thereof.

I claim:

The ornamental design for a showcase, as shown.
